CLAIM

The ornamental design for a thin LED wall pack luminaire as shown and described.

DESCRIPTION

FIG. 1 is a front isometric view of a first embodiment of the thin LED wall pack luminaire;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is a back isometric view thereof;

FIG. 9 is a front isometric view of a second embodiment of the thin LED wall pack luminaire;

FIG. 10 is a front view thereof;

FIG. 11 is a back view thereof;

FIG. 12 is a left view thereof;

FIG. 13 is a right view thereof;

FIG. 14 is a top view thereof;

FIG. 15 is a bottom view thereof; and,

FIG. 16 is a back isometric view thereof.

The evenly spaced broken lines in the figures illustrate portions of the article which form no part of the claimed design. The first embodiment of the article is shown with a symbolic break in its width as illustrated with the dash-dot broken lines. The appearance of any portion of the article between the break lines forms no part of the claimed design.

1 Claim, 12 Drawing Sheets
